UNITED STATES PATENT OFFICE

JAMES A. McBRIDE, OF SALEM, WEST VIRGINIA, ASSIGNOR TO THOMAS McBRIDE GLASS WORKS, INC., OF SALEM, WEST VIRGINIA, A CORPORATION OF WEST VIRGINIA

DESIGN FOR A DRAWER PULL

Application filed October 9, 1930. Serial No. 37,206. Term of patent 7 years.

To all whom it may concern:

Be it known that I, JAMES A. McBRIDE, a citizen of the United States, residing at Salem, in the county of Harrison and State of West Virginia, have invented a new, original, and ornamental Design for a Drawer Pull, of which the following is a specification, reference being had to the accompanying drawing, forming a part thereof.

In the accompanying drawing:

Figure 1 is a top plan view of the drawer pull, showing my new design;

Figure 2 is a side elevation thereof;

Figure 3 is a bottom plan view thereof;

Figure 4 is a section on the line 4—4 of Figure 1;

Figure 5 is a section on the line 5—5 of Figure 1;

Figure 6 is an end elevation;

Figure 7 is a section on the line 7—7 of Figure 1;

Figure 8 is a section on the line 8—8 of Figure 2.

I claim:

The ornamental design for a drawer pull substantially as shown.

JAMES A. McBRIDE.
